UNITED STATES PATENT OFFICE.

JOHN CATRON, OF ROSENBERG, TEXAS.

BURNER.

1,276,619.

Specification of Letters Patent.

Patented Aug. 20, 1918.

Application filed January 12, 1918. Serial No. 211,584.

To all whom it may concern:

It is known that I, JOHN CATRON, a citizen of the United States, residing at Rosenberg, in the county of Fort Bend and State 5 of Texas, have invented new and useful Improvements in Burners, of which the following is a specification.

The object of the invention is to provide a simple and relatively inexpensive burner 10 adapted for use in connection with heating and cooking stoves and the like, and designed for the use of kerosene or similar oil as a fuel, the arrangement of the parts being such as to cause the vaporization of the oil 15 so that it may be burned as a gas with economy as to the amount used in proportion to the results secured.

Further objects and advantages of the invention will appear in the course of the following description, it being understood that changes in form and proportion may be resorted to within the scope of the appended 20 claims, without departing from the spirit of the invention.

25 In the drawing:

Figure 1 is a longitudinal sectional view of a burner constructed in accordance with a preferred embodiment of the invention,

Fig. 2 is a plan view of the same.

30 The burner consists essentially of a retort or converter 10 which, as illustrated may be of cylindrical or tubular form having the terminal caps 11 which are shown as threaded upon the extremities of the body portion 35 of this element, a feed pipe 12 which is preferably disposed vertically, and into which discharges a feed tube 13 having a suitable controlling valve 14, and a burner tube 15 which, like the feed pipe, is in communication 40 with the retort or converter, and is provided with an outlet nozzle 16 preferably of reduced diameter so as to produce a jet arranged to discharge against a deflector 17 which has the effect of distributing the 45 flame and heat so as to affect the retort or converter substantially throughout its length.

The burner tube as shown, is curved in form to dispose its outlet on an upwardly 50 inclined line for proper coöperation with the deflector, and the depressed or looped portion thereof indicated at 18 is adapted to retain temporarily a portion of the liquid fuel when the burner is started, so that vaporization may occur promptly when fuel 55 in the initial ignition pan 19 is lighted.

This pan is provided with an absorbent pad 20 and to saturate the same preparatory to lighting the burner, the liquid fuel is caused to flow from the retort or converter down 60 through the burner pipe and out through the nozzle thereof, as will be obvious, and as before noted that portion of the liquid fuel which remains in the goose-neck or depressed portion of the burner tube will 65 be exposed directly to the heat of the flame in the pan and will become vaporized quickly to be followed obviously by the heating of the retort to such a degree as to vaporize the fuel therein.

70 Preferably, the burner pipe which enters the retort through an opening in the terminal cap 11 thereof, terminates near the plane of the top or uppermost point of the retort, so that the vapor from the oil may 75 readily gain access thereto, and located at an intermediate point preferably on a horizontal diametrical plane of the retort, said burner pipe is provided with an over-flow vent 21. Also the feed pipe which preferably enters the retort through an opening in the cap 11 at the opposite end of the retort terminates in the same horizontal diametrical plane with the vent 21, and is fitted with a check valve 22 which prevents pressure 80 due to vaporization in the retort from causing a return flow of liquid fuel in the feed pipe to the source of supply, which, though not shown, may be of any well known type, as for example: an elevated 85 tank, or a tank supplied with a sufficient atmospheric pressure to cause the fuel to feed through the tube and pipe to the point of communication with the retort.

85 The elements of the burner as described 90 are compactly arranged, due largely as will be noted to the fact that the feed and burner pipes communicate therewith at opposite ends and serve not only as the means for introducing fuel to the retort and conveying vaporized fuel to the point of use, but also as supports to the retort with reference to the initial ignition pan, so that the device may be readily and conveniently arranged in the fire box of a stove of the ordinary construction.

95 What is claimed is:

1. A burner of the type described having a tubular retort or converter provided with terminal caps, feed and burner pipes fitted 100 in openings in said caps and communicating with the interior of the retort, the

burner pipe being terminated in a plane
near the upper side of the retort and having
an over-flow vent disposed in the horizontal
diametrical plane of the retort, and said
5 feed pipe terminating in a common plane
with said vent and fitted with a check valve,
an initial ignition pan, and a deflector ar-
ranged in the path of discharge from the
burner pipe, the burner pipe adjacent to its
10 discharge end being inclined upwardly from
the plane of the said pan.

2. A burner of the character described in-
cluding an initial ignition pan, a tubular
retort disposed above the pan, closure caps
15 detachably connected to the ends of the re-
tort, a feed pipe connected through the pan
and having the upper end detachably en-

gaged in the adjacent closure cap and serv-
ing as a support for the retort, means for
controlling the flow of liquid through the 20
feed pipe, a burner tube having its upper
end detachably connected to the other ter-
minal cap and being curved and seated in
the pan and having its outer portion up-
wardly inclined, said tube serving as a sup-
port for the retort, a nozzle detachably
mounted in the outer end of the tube, and a
deflector suspended from the retort and dis-
posed in the path of distribution from the
nozzle to distribute the heat with reference 25
to the retort.

In testimony whereof I affix my signature.

JOHN CATRON.
